INVENTOR.

Lee ATTORNEY.

UNITED STATES PATENT OFFICE

JOHN S. STOKES, OF HUNTINGDON VALLEY, PENNSYLVANIA, ASSIGNOR TO STOKES AND SMITH COMPANY, OF PHILADELPHIA, PENNSYLVANIA, A CORPORATION OF PENNSYLVANIA

METHOD OF ASSEMBLING, WRAPPING, AND STAYING COMPOSITE BOXES

Application filed February 15, 1926. Serial No. 88,231.

My invention comprehends the utilization of an individual wrapper, sheet, label, or equivalent, hereinafter generically termed a "wrapper", and particularly a tabbed or reinforced wrapper, for holding a plurality of individual components, sections or elements of suitable material in the form of a box, box top, carton, container structure, or equivalent, hereinafter generically termed a "box".

10 In accordance with my invention, a box is formed or constructed by assembling in suitable relation a plurality of separate individual box-forming components and retaining such components in box-forming position by a previously prepared individual wrapper.

Further in accordance with my invention, there is applied to an individual wrapper a coat of adhesive, as glue, or equivalent, and, before material drying or setting 20 of the adhesive, the coated side of the wrapper is first engaged with a box-forming component destined to form one or more sides of the completed box and thereafter with one or more box-forming components entirely individual and separate from the first-mentioned box-forming component, to the end that all of the box-forming components are maintained in box-forming position by the coated wrapper; and more particularly, prior to 25 engagement of the individual coated wrapper with a box-forming component, there are applied to the coated side thereof a plurality of reinforcing elements or tabs to whose exposed surfaces there is then applied adhesive, and, before material drying or setting of the adhesive coatings, the individual tabbed wrapper is suitably applied to the box-forming components with the tabs or reinforcing elements overlying the box-corners.

40 My invention resides in a method of applying an individual wrapper, and more particularly a tabbed or reinforced individual wrapper, to a plurality of individual box-forming components and to a method of manipulating and assembling simultaneously the individual box-forming components and wrapper to form a completed box.

45 My invention resides in a method of the character hereinafter described and claimed.

50 For an understanding of my method and

for an illustration of my product or article, reference is to be had to the accompanying drawing in which:

Fig. 1 is a plan view illustrative of box-forming components utilizable for forming a 55 box.

Fig. 2 is a plan view of a coated tabbed wrapper.

Fig. 3 is a plan view of a coated tabbed wrapper with a box-forming component adhesing thereto.

Fig. 4 is an elevational view of the upper form block of a wrapping machine, showing box-forming components carried at opposite ends thereof.

Fig. 5 is a perspective view of a tabbed wrapper in registering relation with a box-forming component, the form block structure of a wrapping machine being indicated in dotted lines.

Fig. 6 is a perspective view generally the same as Fig. 5, but showing another position of the form block structure after the wrapper and box-forming component have been engaged one with the other.

Figs. 7 to 11, inclusive, represent, respectively, in perspective the successive stages of a box-forming and box-wrapping operation.

Heretofore, boxes have been constructed from one-piece blanks having cut-out corners. The excess material thus excluded cannot ordinarily be salvaged and, therefore, is an item of expense in the production of boxes ordinarily yielding no return.

In accordance with my invention, the old method of forming a blank from a one-piece blank is discarded and, as a substitute, a plurality of separate and distinct box-forming components are associated with an individual adhesive-coated wrapper in such manner that the wrapper maintains such components in box-forming position. As a result, in practicing my invention, I effect a decided saving in material as well as labor, particularly the cost of the box blank corner-cutting operation.

An individual coated wrapper of any suitable shape or configuration may be utilized for securing the various box-forming components in the desired box-forming position.

The wrapper may be either tabbed or untabbed. If tabbed, the wrapper may be of the general character illustrated in my prior Letters Patent No. 845,205, involving the 5 gluing of reinforcing strips or tabs to an uncoated wrapper, by any suitable mechanism, such, for example, as that of the character disclosed in prior Letters Patent to Reif-
snyder et al., No. 1,060,026, or to Nitsch et al.,
10 No. 1,451,782. With a wrapper of this character, the adhesive holding the tabs to the wrapper is allowed to dry or set, and the tabbed wrappers are stored, as in stacks, until later used in the wrapping operation when 15 each tabbed blank and the exposed faces of the tabs are coated with adhesive, as in an automatic gluing or adhesive-applying machine, and thereupon applied to the box-forming components, as in a wrapping machine of the character disclosed in Letters
20 Patent to Smith No. 691,329 or 778,805 or to Federwitz et al., 1,541,036. Or, and preferably, the both operations of applying reinforcing elements or tabs to the wrapper, 25 and of coating the box-engaging faces of the wrapper and tabs with adhesive, are performed just prior to the application thereof of the box-forming components and before drying or setting of the adhesive coatings as
30 disclosed in my U. S. Patent No. 1,599,500, granted September 14, 1926.

Referring to Fig. 1, there are illustrated three box-forming components, sections or elements of suitable shape or configuration and of 35 suitable material, as box-board, paper, paste-board, cardboard, or other material, destined to form a generally rectangular box after proper manipulation and assembly. As shown, there is provided a main box-forming 40 component A, preferably scored or creased as indicated by the two parallel lines *a*, the scored portions constituting opposite boundaries of a generally rectangular section *b* forming, upon completion of the box, one 45 face thereof, as the bottom. Lying respectively outwardly of the scored portions of box-forming component A, aforesaid, are the substantially duplicate sections *c* and *c*₁ forming, upon completion of the box, oppu-
50 site faces thereof, as the two sides.

The substantially duplicate box-forming components, sections or elements B and B₁ shown in Fig. 1 as lying at each end of box-forming component A, during the forming 55 and wrapping operation hereinafter described, are associated with and connected or secured to said component A in angular relation with their edges in registering relation for forming, upon completion of the box, 60 opposite faces thereof, as the two ends.

In Fig. 2, I have illustrated an individual corner cut wrapper W, consisting of a single sheet of paper or equivalent material, of suitable configuration, for example, as disclosed 65 in a prior patent to myself and another, No.

1,265,273, May 7, 1918, or as shown in my co-pending application Serial No. 89,127 filed February 18, 1926, consisting of a composite wrapper comprising a plurality of component elements secured to each other. As 70 herein shown, wrapper W comprises a bottom section *d* and the front and rear wall sections *e* and *f*. The front wall section *e* comprises the corner lap sections *e*₁ and *e*₂, while the rear wall section *f* comprises the 75 corner lap sections *f*₁ and *f*₂. Bottom section *d* comprises the end wall sections *d*₁ and *d*₂.

Wrapper W is first coated on one face thereof in selected regions or over the entire 80 facial area with glue or equivalent adhesive, the application of the adhesive being made while the wrapper is in a stack thereof or, and preferably, after removal from the stack.

Thereafter, one or more tabs T, of any 85 suitable material as paper of any suitable form and size, is or are applied to that portion of the coated wrapper destined to come into engagement with the edges, corners or other portions of the box for reinforcing or 90 strengthening the completed box, as herein-after described. In the example illustrated, both sides of the tabs T, when applied to wrapper W, are free of adhesive, the adhesive coating upon said wrapper serving to 95 secure the tabs. It will be understood, however, that the wrapper-engaging faces of the tab T may be coated with adhesive before application to the coated wrapper W, though it is preferred; and will ordinarily 100 suffice, that the wrapper-engaging faces of the tabs be uncoated when applied to the coated wrapper.

Tabs T may be severed, as needed, from a suitable ribbon or roll, or may be first formed and piled in stacks and withdrawn as and when required, all as disclosed in my said U. S. Patent No. 1,599,500.

After the tabs have been so applied to the previously coated wrapper W, the box-engaging surfaces of the tabs are coated with adhesive, yielding, as indicated in Fig. 2, a 110 coated wrapper W with adhering coated tabs T.

The tabbed wrapper has now been prepared for application to the box-forming components illustrated in Fig. 1, and such application is preferably made promptly, while the coated wrapper W and its coated tabs T are soft and pliable, and before the 120 adhesive coatings upon the wrapper and tabs have dried, hardened or set.

Initially, engagement may be effected between box-forming component A and the individual wrapper W in such manner that bottom section *b* and side sections *c* and *c*₁ of said component A, respectively, engage and adhere to bottom section *d* and front and rear wall sections *e* and *f* of said wrapper W. 125 As indicated in Fig. 3, the length of box-

5 forming component A, or the distance along a line *a* thereof, is such that the component extends from the apexes of the notches on one side of the wrapper to the apexes of the notches on the other side thereof. Further, 10 the width of component A, or the distance along a line at right angles to the lines *a*, thereof, is such that free portions of the front and rear wall sections *e* and *f* of wrapper W are exposed, Fig. 3. Such exposed 15 sections are tucked around the front and rear sides of the box, as hereinafter described.

When wrapper W is reinforced with tabs T as indicated in Fig. 2 and box-forming component A is engaged therewith in the 15 manner illustrated in Fig. 3, it will be found that the opposite edges of said component at right angles to the lines *a*, thereof, divide tabs T into substantially equal portions, those nearest the center of the wrapper lying 20 between component A and the wrapper while the other portions lie exteriorly of component A and are not engaged thereby.

At the next stage in the operation, a form block or equivalent structure may be so placed as to overlie section *b* of the component A comprised in the composite structure indicated in Fig. 3. The base of this form block corresponds in size with section *b*, and is of a height corresponding generally 25 with the distance across either section *c* or section *c1* of box-forming component A, along a line drawn at right angles to the lines *a*, thereof.

Assuming that the structure shown in Fig. 35 is in a horizontal position with box-forming component A, overlying wrapper W, sections *e*, and *f*, of said component, the portions of wrapper W adhering thereto and the outwardly positioned tabs T are bent 40 upwardly into vertical positions, the scored or creased construction of element A readily permitting this action.

At the next stage in the assembling operation, box-forming components B and B1 45 are located in vertical positions and suitably held at each end of, and in engagement with, the form block, Fig. 7.

Thereafter, the now vertical corner lap 50 sections *e1* and *f1* of wrapper W are folded inwardly into engagement with box-forming component B1 while corner lap sections *e2* and *f2* of said wrapper are likewise folded into engagement with box-forming component B, Fig. 8.

End wall section *d1* of wrapper W is now 55 folded upwardly into engagement with box-forming component B1 and the adhering corner lap sections already folded into engagement therewith. Similarly, end wall section *d2* of said wrapper is folded upwardly 60 into engagement with box-forming component B and its adhering corner lap sections, Fig. 9.

65 Finally, the portions of the wrapper pro-

truding above the upper edges of the now vertical box-forming walls are folded downwardly and into adhering engagement with the interior surfaces of said vertical walls to form the completed box illustrated in Fig. 11.

It will be observed that the various reinforcing tabs T respectively overlie the various dihedral corners of the box and adhere to all the box faces meeting in any corner. As a result, the box corners are reinforced and the set-in box-forming components, ends or elements B and B1 are firmly and securely bound to the main box-forming component, section or element A.

All the foregoing operations may be performed manually. Preferably, however, they will be performed by automatic mechanism. For example, the individual wrappers W, when in a stack, may be operated upon in an automatic adhesive-applying machine, such, for example, as disclosed in Nitsch et al. application Serial No. 69,249, or in the adhesive-applying unit G of Federwitz and Bailey application Serial No. 40,769. The individual coated wrappers, as W, may then be tabbed by any suitable mechanism, including such, for example, as of the character disclosed in the aforesaid Letters Patent No. 1,060,026, or 1,451,782, or, and preferably, during pauses in their travel from the gluing machine G to the wrapping machine W, in a system such as disclosed in the aforesaid Federwitz et al. application Serial No. 40,769, as by suitable mechanism associated with the conveyor or feeding unit C of that system. Accordingly, individual tabbed wrappers W are fed in succession in proper relation between the form block structure of a wrapping machine as shown in broken lines in Fig. 5 and comprising the upper and lower form blocks F and F1 operated as well understood in suitable timed relation by the usual rods *f4* and *f5*.

The wrapping machine aforesaid may be of any suitable character as, for example, of the same general type disclosed in the aforesaid Smith Patents 691,329 and 778,805, or the aforesaid Federwitz et al. Patent 1,541,036; or, and preferably, in a wrapping machine W of the aforesaid Federwitz et al. application, Serial No. 40,769, to which the tabbed wrappers are fed in succession by the conveyor unit C.

The usual guide rods *g4* comprised in the wrapping machine support rods or members *m4* extending laterally from said guide rods. Carried respectively by members *m4* are the holding fingers or clips *c4*. As well understood in the art, guide rods *g4* move relative to rod *f4* whereby, when form block F is in its upper region of travel, holding fingers *c4* are positioned entirely thereabove. However, as the form block pursues its downward course, the ends of the holding fingers move

downwardly into the position illustrated in Fig. 4.

Preferably box-forming components B and B1 are piled in previously prepared horizontally-disposed stacks S and S1, Fig. 4, suitably arranged at the same ends of the form immediately thereafter, holding fingers c4. While form block F is in its upper region of travel aforesaid, individual box-forming components are suitably removed from the stacks S and S1 and transferred into engagement with the ends of the form block. Immediately thereafter, holding fingers c4 move into the position indicated in Fig. 4, whereby said components are positively retained in engagement with the ends of form block F.

Box-forming components A may be individually fed or transferred in succession between the upper and lower form blocks of the wrapping machine in any suitable manner, preferably, however, in a system such as disclosed in the aforesaid Federwitz et al. application, Serial No. 40,769, as by the box-advancing structure or rods therein disclosed for delivering individual box-structures beneath the upper form block.

Accordingly, in the wrapping machine, an individual tabbed wrapper W and a box-forming component A come into proper register with each other in proper relation to the descending form block F to which the box-forming components B and B1 are secured during its descending movement, Fig. 5.

In Fig. 6, a stage of the operation is illustrated wherein the upper form block F has effected engagement of wrapper W and box-forming component A and the composite structure has been moved into engagement with the lower form block F1.

Figs. 7 to 11, inclusive, illustrate succeeding stages in the box-assembling and wrapping operation, Fig. 11, showing the finished article, a wrapped box B2. By the operations described, either manual or as performed by the automatic mechanism of the wrapping machine, the wrapper flaps are applied to the box-forming components in suitable sequence, the tabs T being at suitable times applied to and worked around the box corners.

Although the foregoing description is limited to the formation of a box from a specified number of box-forming components, sections or elements, it shall be understood that my invention comprehends the utilization of a greater or smaller number of such components. Further, it shall be understood that my invention also comprehends the manipulation and assembly of a desired number of box-forming components in other ways specifically different from the corresponding disclosure of this application.

Likewise, it shall be understood that types of individual wrappers may be utilized differing from the wrapper W herein disclosed,

and that in the region or regions where the reinforcing tab or tabs is or are applied may be varied as desired to effect proper reinforcing or strengthening in the desired regions of the completed composite box structure. 70

It shall also be understood that my invention is not to be restricted to the utilization of a wrapper that is tabbed, strengthened or otherwise reinforced, since at times and under certain conditions, it may be desirable to utilize a plain wrapper wherein all strengthening or reinforcing structure or tabs is omitted. Plain wrappers of such character may be fed in succession to a wrapping machine, as aforesaid, in any desired manner, 80 for example, as described above with respect to the delivery of tabbed or reinforced wrappers.

It shall also be understood that the tabbed wrapper may be applied to the box-forming components after the adhesive securing the tabs to the wrapper has hardened or set although, as indicated above, it is desirable that application of the wrapper to the box-forming components be effected before the adhesive coating on the wrapper has materially hardened or set. 85

When utilizing a composite wrapper, for example, as illustrated and described in my aforesaid co-pending application, Serial No. 89,127, filed February 18, 1926, it is preferable that the application of the wrapper to the box-forming components be effected prior to material hardening or setting of the adhesive with which the wrapper components are 100 coated. 95

In the wrapping operation heat may be applied, as disclosed in my co-pending application Serial No. 71,178, filed November 24, 1925, to set or to hasten setting or drying of 105 the adhesive which holds the tabs, when used, to the wrapper and of the adhesive on the box-engaging faces of the wrapper and tabs, when used.

The preferred operation is as described, 110 namely, that of utilizing the individual wrapper, and the tabs, when used, as the sole reinforcing or retaining structure for the box-forming components. It shall be understood, however, that the box-forming components 115 may be first assembled and maintained in box-forming position by suitable structure, as by webs overlying the various corners, and that thereafter the individual wrapper, or the wrapper and the adhering tabs, may be applied in any suitable manner. 120

Inasmuch as a box top is substantially similar to that part of the entire box commonly utilized as the receptacle, it shall be understood, in the appended claims, that the expression "box bottom" is descriptive either of the box top or the bottom of the receptacle. 125

What I claim is:

1. The method of forming a box, which comprises applying a wrapper to separate, 130

unattached box-forming walls and to a box bottom to hold them in box-forming position.

2. The method of forming a box, which comprises coating an individual corner cut wrapper with adhesive, and, before material setting of the adhesive, applying said wrapper to a plurality of unattached box-forming components to hold them in box-forming position with the corner laps at the ends of the 10 wrapper side panels overlying the respective end walls of the box.

3. The method of forming boxes, which comprises transporting individual wrappers in succession, and applying an individual 15 wrapper to, unattached box-forming walls and to a box bottom to hold the walls to each other and to the box bottom.

4. The method of holding a plurality of 20 separate, unattached box-forming walls and a box bottom in box-forming position, which comprises applying a tabbed wrapper to said walls and bottoms with the tabs overlying corners of the box.

5. The method of holding a plurality of 25 separate, unattached box-forming walls and a box bottom in box-forming position, which comprises coating a tabbed wrapper with adhesive, and applying the coated tabbed wrapper to said walls and bottoms with the tabs overlying corners of the box.

6. The method of holding a plurality of 30 separate, unattached box-forming walls and a box bottom in box-forming position, which comprises coating a tabbed wrapper with adhesive, and, before material setting of the adhesive, applying the coated tabbed wrapper to said walls and bottoms with the tabs overlying corners of the box.

7. The method of forming a box, which 40 comprises, in any sequence, the steps of applying tabs to a wrapper with adhesive, applying adhesive to the box-engaging faces of said tabs, applying adhesive to the box-engaging face of the wrapper, and, before material setting of the adhesive coating on the wrapper, applying the coated tabbed wrapper to a plurality of separate unattached box forming walls and a box bottom to hold them in box-forming position.

8. The method of forming a box, which 50 comprises, in any sequence, the steps of applying tabs to a wrapper with adhesive, applying adhesive to the box-engaging faces of said tabs, applying adhesive to the box-engaging face of the wrapper, and, before material setting of any of the adhesive coatings, applying the coated tabbed wrapper to a plurality of separate, unattached box-forming walls and a box bottom to hold them in 55 box-forming position.

9. The method of forming a box, which 60 comprises, the steps of applying adhesive to a wrapper, and thereafter, in either sequence, applying tabs to the coated wrapper and 65 coating the box-engaging faces of said tabs

with adhesive, and, before material setting of any of the adhesive coatings, applying the coated tabbed wrapper to a plurality of separate, unattached box-forming walls and a box bottom to hold them in box-forming position. 70

10. The method of forming a box, which comprises, the steps of applying adhesive to a wrapper, applying tabs to the coated wrapper, applying adhesive to the box-engaging faces of said tabs, and, before material setting of any of the adhesive coatings, applying the coated tabbed wrapper to a plurality of separate unattached box-forming walls and a box bottom to hold them in box-forming position. 75

11. The method of forming a box, which comprises, bringing the edges of individual box-forming walls into non-adhesive, abutting relation with a box-forming component 80 destined to form the box bottom, and while so held, applying a wrapper around the edges of said component and walls to hold them in box-forming position.

12. The method of forming a box, which 85 comprises, in either sequence, effecting non-adhesive engagement between the edge of a box-forming wall and the edge of a box-forming component destined to form the box bottom and effecting engagement between a portion of a wrapper and said component, thereafter applying sections of the wrapper to the respective box walls, and folding the outer portions of said wrapper sections over said box walls and into engagement with 90 their interior surfaces.

13. The method of forming boxes, which 95 comprises transporting individual tabbed wrappers in succession, in either sequence, effecting non-adhesive engagement between the edge of a box-forming wall and the edge of a box-forming component destined to form the box bottom and effecting engagement between a portion of an individual tabbed wrapper and said component, and thereafter applying sections of the tabbed wrapper to the respective box walls with the tabs overlying corners of the box. 100

14. The method of forming a box, which 105 comprises effecting engagement between a section of an adhesive-coated wrapper and a box-forming component destined to form the bottom of the box, and thereafter applying other wrapper sections to separate and individual box-wall-forming components 110 unattached to said first named component.

15. The method of forming a box, which 115 comprises effecting engagement between a section of a tabbed adhesive-coated wrapper and a box-forming component destined to form the bottom of the box, and thereafter applying other wrapper sections to box-wall-forming components unattached to said first named component with the tabs overlying corners of the box. 120

16. The method of forming a box, which comprises applying a corner-cut wrapper to unattached box-forming components with the corner-laps at the ends of the wrapper side panels overlying the respective end walls of the box, whereby said components are held in box-forming position by the wrapper. 5
17. The method of forming boxes, which comprises transporting in succession to a 10 wrapping station individual wrappers, each having on one face a fluid adhesive coating, and at said station applying a wrapper, while its adhesive coating is still fluid, to separate, unattached box-wall forming components and to a box-bottom component whereby said components are held in box-forming position by the wrapper. 15
18. The method of forming boxes, which comprises transporting in succession individual tabbed wrappers, each having on one 20 face a fluid adhesive coating, and securing a tabbed wrapper while the adhesive coating on the wrapper is still fluid, to unattached box-forming components whereby said components are held in box-forming position by the tabbed wrapper. 25
19. The method of forming boxes, which comprises transporting in succession individual tabbed wrappers, each having on one 30 face a fluid adhesive coating, and securing an individual tabbed wrapper, while the adhesive coating on the wrapper and tabs is still fluid, to unattached box-forming components whereby said components are held in box-forming position by the tabbed wrapper. 35
20. The method of forming boxes, which comprises transporting in succession individual adhesive-coated wrappers having 40 tabs adhering thereto at the regions of union of wrapper sections and turn-in flaps, and applying each of the individual tabbed wrappers, while the adhesive coating on the wrapper is still fluid, to successive groups of unattached box-forming components to hold 45 them in box-forming position and with the tabs overlying corners of the box. 50
21. The method of forming a box which comprises in either sequence effecting non-adhesive engagement between the edge of a 55 box-forming wall and the edge of a box-forming component, destined to form the box bottom and a box wall, and effecting engagement between a wrapper portion and said component, and thereafter applying another portion of said wrapper to said box-forming wall. 53
22. The method of forming a box which 60 comprises in either sequence effecting non-adhesive engagement between the edges of box-forming walls and the edges of a box-forming component, destined to form the box-bottom and box walls, and effecting engagement between a wrapper portion and 65
- said component, and thereafter applying other portions of said wrapper to said box-forming walls. 70
23. The method of forming a box which comprises in either sequence effecting non-adhesive engagement between the edge of a box-forming wall and the edge of a box-forming component, destined to form the box bottom and a box wall, and effecting engagement between a portion of a tabbed wrapper and 75 said component, and thereafter applying another portion of said tabbed wrapper to said box-forming wall with one or more edges of the box reinforced by tabbing of said wrapper. 80
24. The method of forming a box which comprises in either sequence effecting non-adhesive engagement between the edges of box-forming walls and the edges of a box-forming component, destined to form the box bottom and box walls, and effecting engagement between a portion of a tabbed wrapper and 85 said component, and thereafter applying other portions of said tabbed wrapper to said box-forming walls with one or more edges of the box reinforced by tabbing of said wrapper. 90
25. The method of forming a box from a plurality of separate, unattached wall-forming components and a box-bottom component, which comprises the steps of applying adhesive to an individual wrapper, applying adhesive to tabs, and before setting of the adhesive, applying the wrapper and tabs to said 95 wall-forming and box-bottom components to hold them in box-forming position. 100
26. The method of forming a box from a pair of separate, unattached components adapted to form opposite walls of a box and 105 a component adapted to form a box-bottom and a second pair of box-walls, which comprises the simultaneous steps of moving box-walls to box-forming position, and applying a wrapper to box-components to hold them 110 in box-forming position. 110
27. The method of forming a box from separate, unattached wall-forming components and a box-bottom component, which comprises the simultaneous steps of bringing the box-wall and box-bottom components into box-forming position, and applying a wrapper to box-components to hold them permanently in box-forming position. 115
28. The method of forming a box from a plurality of separate, unattached wall-forming components and a box-bottom component, which comprises applying adhesive to an individual wrapper, applying adhesive to tabs, and before setting of the adhesive the 120 simultaneous steps of moving box-walls to box-forming position, interposing tabs between the wrapper and box structure, and applying the wrapper to box-components to hold them in box-forming position. 125
29. The method of forming a box from a plurality of separate, unattached wall-forming components and a box-bottom component, which comprises applying adhesive to an individual wrapper, applying adhesive to tabs, and before setting of the adhesive the simultaneous steps of moving box-walls to box-forming position, interposing tabs between the wrapper and box structure, and applying the wrapper to box-components to hold them in box-forming position. 130

29. The method of forming a box having a plurality of vertical walls and a bottom, which comprises the concurrent steps of applying a wrapper to and bringing into box-forming relation separate unattached components adapted to form vertical box-walls. 5 70
30. The method of forming a box from a plurality of separate unattached box-forming components, which comprises the concurrent steps of applying a wrapper, staying, and bringing the box-forming components into box-forming relation. 10 75
31. The method of forming a box from a plurality of separate, unattached box-forming components, which comprises applying a wrapper the box-forming components to hold them in box-forming position, and folding staying structure over the top of and into engagement with the inside of the box. 15 80
32. The method of forming a box from a plurality of box-forming components, which comprises concurrently moving separate, unattached box-forming components to box-forming position and applying a wrapper thereto, and during the wrapping operation folding staying structure over the top of and into engagement with the inside of the box. 20 85
33. The method of forming a box from a plurality of box-forming components, which comprises concurrently moving separate unattached box-forming components to box-forming position and applying a wrapper thereto, and during the wrapping operation folding tabs over the top of and into engagement with the inside of the box at corners thereof. 30 90
34. The method of forming a box from a plurality of box-forming components, which comprises moving separate, unattached box-forming components to box-forming position, joining adjacent unattached components by tab structure projecting beyond the free edges thereof, applying a wrapper, and during the wrapping operation folding the projecting tab structure over said edges into engagement with said adjacent components. 40 95
35. The method of forming a box from a plurality of box-forming components, which comprises moving separate, unattached box-forming components to box-forming position, joining adjacent unattached components by tab structure projecting beyond the free edges thereof, and thereafter folding the projecting tab structure over said edges in engagement with said adjacent components. 50 100
36. The method of forming a box from a plurality of box-forming components, which comprises moving separate unattached box-forming components to box-forming position, joining adjacent unattached components by tabs projecting beyond the free edges thereof, and thereafter simultaneously folding the projecting tabs over said edges in engagement with said adjacent components. 60 105
37. The method of forming a box from a plurality of separate, unattached box-forming components, which comprises folding a wrapper and thereby effecting movement of separate, unattached box-forming components to box-forming position in which they are held by the wrapper. 70 110
38. The method of forming a box from a plurality of separate, unattached box-forming components, which comprises folding a wrapper and thereby effecting movement of tabs and of separate unattached box-forming components to box-forming position in which they are held by the tabs and wrapper. 75 115
39. The method of forming a box from a plurality of separate, unattached box-forming components which comprises folding a tabbed wrapper and thereby effecting movement of separate, unattached box-forming components to box-forming position in which they are held by the tabs and wrapper. 80 120
40. The method of forming a box from a plurality of separate, unattached box-forming components, which comprises folding a wrapper and thereby effecting movement of separate, unattached box-forming components to box-forming position and of interposed tabs, the wrapper and tabs retaining the separate box-components in said box-forming position. 85 125
41. The method of forming a box having a plurality of vertical walls and a bottom which comprises, assembling separate, unattached box components upon a form, and by application of an individual wrapper to said components while upon said form, concurrently attaching said components in box-forming position and covering the box formed thereby. 100 130
42. The method of forming a box having a plurality of vertical walls and a bottom which comprises assembling separate, unattached box components at a box fabricating station, and at said station, applying an individual wrapper to said assembled components concurrently to attach said components in box-forming position and to stay and wrap the box formed thereby. 105 135
43. The method of forming a box having a plurality of walls and a bottom, which comprises the concurrent steps of bringing separate, unattached components adapted to form box walls and a box bottom into box-forming position, and adhesively applying sheet material to attach said components to each other and to hold them permanently in box-forming position. 115 140
44. The method of forming a box having a plurality of vertical walls and a bottom, which comprises assembling separate, unattached box-wall components and a box bottom in box-forming position at a box-forming station, and at said station adhesively applying sheet material to attach said components to each other in box-form- 125 145

ing position and to stay the box formed thereby.

45. The method of forming a box having end and side walls and a bottom, said walls detached from each other and at least one of them detached from said bottom, which comprises bringing said walls and bottom into box-forming position, and while said walls and bottom are so detached from each other and in box-forming position attaching them to each other by sheet material adhesively engaging the neighboring side and end walls and embracing the corners formed by their adjacent edges, and adhesively engaging at least one of said walls and said bottom and embracing the corner formed by their adjacent edges, to hold said walls and bottom permanently in box-forming position.

JOHN S. STOKES.

ing position and to stay the box formed thereby.

45. The method of forming a box having end and side walls and a bottom, said walls detached from each other and at least one of them detached from said bottom, which comprises bringing said walls and bottom into box-forming position, and while said walls and bottom are so detached from each other and in box-forming position attaching them to each other by sheet material adhesively engaging the neighboring side and end walls and embracing the corners formed by their adjacent edges, and adhesively engaging at least one of said walls and said bottom and embracing the corner formed by their adjacent edges, to hold said walls and bottom permanently in box-forming position.

CERTIFICATE OF CORRECTION.

Patent No. 1,796,630.

Granted March 17, 1931, to

JOHN S. STOKES.

It is hereby certified that error appears in the printed specification of the above numbered patent requiring correction as follows: Page 4, line 7, strike out the words and comma "mediately thereafter," and insert instead block structure as are the; page 5, line 15, claim 3, after the word "to" and before the comma insert the word "separate"; and that the said Letters Patent should be read with these corrections therein that the same may conform to the record of the case in the Patent Office.

Signed and sealed this 14th day of April, A. D. 1931.

(Seal)

M. J. Moore,
Acting Commissioner of Patents.
